UNITED STATES PATENT OFFICE.

WILLIAM KRUTZSCH, OF DAYTON, OHIO, ASSIGNOR TO THE BUCKEYE IRON AND BRASS WORKS, OF SAME PLACE.

OIL-CUP.

SPECIFICATION forming part of Letters Patent No. 334,710, dated January 19, 1886.

Application filed December 17, 1885. Serial No. 185,950. (No model.)

To all whom it may concern:

Be it known that I, WILLIAM KRUTZSCH, a citizen of the United States, residing at Dayton, in the county of Montgomery and State of Ohio, have invented new and useful Improvements in Oil-Cups, of which the following is a specification.

My invention relates to an improved stopper for oil-cups or lubricating devices; and it consists of an oil-cup having a filling-orifice at one end, and inclosing a spring-actuated stopper which presses outward within the filling-orifice, thereby securely closing the cup, but allowing the said filling-orifice to be uncovered by pressing the spring-stopper inward and to one side.

The invention is illustrated in the annexed drawings, in which Figure 1 is a vertical section of my improved lubricating-cup on the line *x x* of Fig. 4. Fig. 2 is a sectional detail view taken on the line *y y* of Fig. 4, the filling-orifice being shown closed. Fig. 3 is a side elevation of the cup, partly in section, on the line *y y* of Fig. 4, the filling-orifice being shown open with the stopper pressed inward and to one side. Fig. 4 is a plan view of the oil-cup.

Referring to the drawings, A represents a cylinder of glass or other material, preferably transparent. To the upper end of this cylinder is attached a cap, B, and the lower end is closed by a plate, C, having on its outer face a threaded tubular shank, C', by which the cup is connected with the mechanism to be lubricated. On the inner face of this bottom plate, C, is formed a tubular stem, D, which passes through the oil-cup and its cap B, and is secured thereto by a nut, E, on the outer side of said cap.

F is the feed-rod, which works in the tubular stem D and controls the flow of oil from the cup through an outlet, H, at the lower end of said stem. The feed-rod is provided with a milled head, R, and its lower end is threaded and grooved at H', so that by means of its head R it may be turned sufficiently to cause said groove H' to register with the oil-outlet H and enable the oil to be fed from the cup. By turning the feed-rod F in the opposite direction the flow of oil will be arrested.

G' represent packing-rings, of cork or

other material, placed at each end of the cylinder. The cap B has a filling-orifice, I, through which the cup is supplied with oil. This filling-orifice is closed by a spring-actuated stopper, J, which is arranged within the oil-cup in such a manner as to be pressed inward and away from the opening I when it is desired to replenish the cup. The stopper J is formed with a tubular portion, K, which fits over a 6c collar, M, on a rod, L, the lower end of which is seated in a socket, N, on the inner side of the bottom plate, C. The upper end of the stopper is provided internally with a guide-socket, Q, which receives the upper end of the 65 rod L when the stopper is pressed down. Within the tubular portion K of the stopper and surrounding the rod L is a spirally-coiled spring, P, one end of which rests on the collar M, while the other end bears against a 7c shoulder, T, at the upper socketed end of the stopper. The spring P is thus inclosed in the stopper and is not liable to become broken or disarranged. The upper end of the stopper is provided with a button or finger-piece, 75 O, which projects laterally from a neck, S, that connects with the stopper and projects through the filling-orifice. When the stopper J and its rod L are in line with the filling-orifice I, the stopper will be supported and pressed 80 outward by the spring P so as to enter the orifice I from its inner side, and thus securely close the cup. It will be observed that the edge of the opening I is beveled downward to correspond with and fit a similar beveled surface on the exterior of the stopper. When the stopper is in place, therefore, as shown in Figs. 1 and 2, it completely plugs the orifice I and effectually prevents the escape of oil or the entrance of dirt or other foreign matter. 85 By pressing the button or finger-piece O downward and to one side the neck S will be carried down through the opening I until the upper end of the stopper engages the under side of the cap B at the side of the opening, as 90 shown in Fig. 3, and thus uncovers said opening or filling-orifice so as to permit filling or refilling the cup. While the stopper is thus engaged with the cap the filling-orifice will remain open without any necessity of holding the 95 button or finger-piece O.

In order to close the oil-cup it is only nec-

essary to give the button O a slight push, when the stopper J will immediately spring into engagement with the filling orifice.

A spring-actuated stopper of the form described is adapted to securely close the oil-cup at all times, and is not liable to become disarranged or jarred out of place. This construction also renders it impossible for the spout of the filling-can to enter the filling-orifice I so far as to obstruct the free exit of the displaced air.

What I claim as my invention is—

1. In an oil-cup, the combination, with a cap having a filling-orifice, of an internal 15 spring-actuated stopper having a finger-piece that projects through said filling-orifice, substantially as described.
2. In an oil-cup, the combination, with a cap having a filling-orifice, of a laterally-movable 20 spring-actuated stopper inclosed in said cup, and provided with a finger-piece projecting through said filling-orifice, and a movable rod for supporting said stopper, substantially as described.
- 25 3. In an oil-cup, the combination of a cap having a filling-orifice, a spring-actuated stopper inclosed in the oil-cup and having a finger-piece and a connecting-neck projecting

through said filling-orifice, and a rod for supporting and guiding the stopper, said rod being seated at the bottom of the cup and having a collar for supporting the stopper-spring, substantially as described.

4. In an oil-cup, the combination of a cap having a filling-orifice, a bottom plate provided with a socket, a tubular stopper arranged within the oil-cup and having a finger-piece projecting through the filling-orifice, a movable rod seated in the socket of the bottom plate and having a collar, and a spring 40 inclosed in the stopper and surrounding the upper end of said rod, substantially as described.

5. In an oil-cup, the combination of the cylinder A, the cap B, having a filling-orifice, I, 45 the bottom plate, C, provided with socket N, the tubular stopper J, the rod L, having collar M, and the spring P, substantially as described.

In testimony whereof I affix my signature in presence of witnesses.

WILLIAM KRUTZSCH.
